PROPANE GAS LANTERN

Milo E. Webster, Rochester, N. Y., assignor to Otto Bernz
Co., Inc., Rochester, N. Y., a corporation of New
York

Application March 23, 1955, Serial No. 35,177

Term of patent 14 years

(Cl. D48—24)

Fig. 1 is a side elevational view of a propane gas lantern showing my new design;

Fig. 2 is a top plan, the fitting shown on the right of Fig. 1 having been omitted for convenience of illustration;

Fig. 3 is a side elevation view as seen from the left of Fig. 1 the handle as shown in Fig. 1 having been omitted for convenience of illustration; and

Fig. 4 is a side elevation view as seen from the right of Fig. 1 the handle as shown in Fig. 1 having been omitted for convenience of illustration.

I claim:

The ornamental design for propane gas lantern, as shown.
